OF WEST VIRGINIA.

INTERNAL-COMBUSTION ENGINE.

1,400,122.

Specification of Letters Patent. Patented Dec. 13, 1921.

Application filed November 14, 1917. Serial No. 202,034.

To all whom it may concern:

Be it known that I, NIKLAS WINBLAD, a citizen of the United States, and a resident of Stepney, in the county of Fairfield and 5 State of Connecticut, have invented an Improvement in Internal-Combustion Engines, of which the following description, in connection with the accompanying drawings, is a specification, like characters on the drawings representing like parts.

This invention relates to internal combustion engines, and is more particularly, though not exclusively, concerned with a valve mechanism especially adapted for use 15 with high speed, high compression engines of the modern type, in which the valves are placed alongside and close to the cylinders, to enable the combustion chambers to be decreased in size, without unduly reducing 20 their depth.

My invention will be best understood by reference to the following description, when taken in connection with the accompanying drawings of one specific embodiment there- 25 of, while its scope will be more particularly pointed out in the appended claims.

In the drawings:

Figure 1 is a vertical, cross-sectional view 30 of an internal combustion engine embodying my invention;

Fig. 2 is a detail plan of one pair of valve lifter guides, and the yoke and stud which holds them in place; and

Fig. 3 is a detail sectional view on line 35 3-3 of Fig. 1, but with the valve lifters omitted.

Referring to the drawings, and to the embodiment of my invention which is illustrated therein, I have shown for purposes of 40 exemplification an internal combustion engine of the T-head type, having a cylinder 4 provided with a combustion chamber 5, having laterally offset valve chambers 6-6, although it should be distinctly understood 45 that my invention is by no means limited to engines of the T-head type, but may be used in connection with engines of the L-head type and possibly others. The general features of the engine are, or may be, 50 of common form, and herein include a piston 7 working in the cylinder 5, and connected by a connecting rod 8 to a crank-

pin 9 of a crank-shaft 10, the latter being mounted in suitable bearings 11 in a crank-case 12. Also mounted in suitable bearings 55 in the crank case are two cam-shafts 13, provided with cams 14 to operate valve lifters 15 in a usual and well-known manner, thereby to actuate valves 16 coöperating with valve seats 17 in the offset chambers 6. 60 These valves act to control the admission of combustible mixture to and the exhaust of the spent gases from the cylinder in a manner too well known to require further 65 description.

It should be observed that the axis of the cam shaft is located at a greater distance from the axis of the cylinder than the distance from the center of the valve seat to said axis. This enables the combustion 70 chamber to be of the least possible width for a given diameter of valve, while still providing ample space for the valve-actuating mechanism at one side of the cylinder. This is herein accomplished by arranging 75 the valve and valve lifter so that their common axis AA is at an angle to the axis BB of the cylinder. Heretofore, this arrangement has introduced difficulties in the guiding of the valve lifters, but by the arrangement which I shall now describe, all of the advantages of the inclined arrangement of the valves are preserved, and the difficulties referred to are obviated. To these ends, I have herein provided valve-lifter guides 18, 80 each of which has a cylindrical bore 19 to receive and guide the valve-lifter, the axis of this bore being, of course, at an angle to the axis of the cylinder.

To avoid serious difficulties in machining 90 the crank-case, where it forms a support for the valve-lifter guide, the outside of the latter is arranged parallel with the axis of the cylinder. In the present example, the crank-case is provided with a cylindrical bore 20, to receive and form a socket for a corresponding cylindrical portion 21 of the valve lifter guide, while the latter is provided with a supporting flange 22 at right angles to the axis of the cylinder. This 100 flange rests upon a supporting surface 23, also at right angles to the axis of the cylinder.

Thus it is evident that, while the valve

and valve-lifter are inclined at an angle to the axis of the cylinder, and the internal guiding surface of the valve-lifter guide is correspondingly inclined, its exterior is shaped to provide a socket parallel with the cylinder and a seat at right angles therewith, thus greatly simplifying the operation of machining the crank-case casting, a matter which has heretofore been attended with great difficulty in engines of the inclined valve type.

Since the bore 19 of the valve lifter-guide is at an angle to the bore 20 in the crank case, it is important that the guide be held against turning movement; otherwise the valve lifter guide would be apt to turn around in its seat, and the valve lifter would not be in proper position for coöperation with the valve. As a means to prevent any such turning movement, I have herein provided a stud 24 interlocking with the flanges of one pair of guides, as best shown in Figs. 2 and 3. A nut 25 threaded onto the stud engages a usual yoke 26, the latter having pairs of arms 27 resting on the flanges 22, and serving to clamp the latter against the supporting surface 23. By this means, the valve-actuator guides are firmly held in their sockets, and prevented from turning. The valve lifters and guides may be readily removed at any time by simply unscrewing the nuts 25 and lifting the yokes 26, after which the guides may be withdrawn in an upward direction, and when these parts are replaced, the flanges 22 are once more interlocked with the stud 24, so that the bores 19 are accurately positioned in alinement with the valves.

While I have herein shown and described one specific form or embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.

Having thus described my invention, what I claim and desire by Letters Patent to secure is:

1. An engine comprising, in combination, a cylinder having a laterally offset valve chamber and a pair of valve seats, a piston working in said cylinder, a pair of valves coöperating with said seats, valve actuating mechanism including a shaft whose axis is located at a greater distance from the axis of said cylinder than the distance from the centers of said valve seats to said axis, a pair of valve-actuators separated by said

shaft, a pair of valve-actuator guides arranged parallel with the axis of said cylinder, and means to predetermine the position of said guides with reference to movement about their axes. 70

2. An engine comprising, in combination, a cylinder having a laterally offset valve chamber and a pair of valve seats, a piston working in said cylinder, a pair of valves coöperating with said seats, valve-actuating mechanism including a shaft whose axis is located at a greater distance from the axis of said cylinder than the distance from the centers of said valve seats to said axis, a pair of valve-actuators operated by said shaft, a pair of valve-actuator guides having outer circumferential surfaces arranged parallel with the axis of said cylinder and having inner valve-actuator guiding surfaces arranged at an angle to the axis of said cylinder, a support provided with openings whose internal surfaces form sockets for said outer circumferential surfaces of said guides, and means to predetermine the position of said guides and to insure alinement of their guiding surfaces with said valves. 80

3. An engine comprising, in combination, a cylinder having a piston working therein, a valve having its axis disposed lengthwise of and at an angle to the axis of said cylinder, a valve-actuator axially alined with said valve, a valve-actuator guide having one axis alined with said valve and valve-actuator and having another axis parallel with the axis of said cylinder, a guide mounting provided with a guide-receiving opening having an axis parallel with the axis of said cylinder, and means interengaging with said guide to position the same, and to insure alinement of the axis of said guide with the axis of said valve. 90

4. An engine comprising, in combination, a cylinder having a piston working therein, a valve having its axis disposed lengthwise of and at an angle to the axis of said cylinder, a valve-actuator axially alined with said valve, a valve-actuator guide having one axis alined with said valve and valve-actuator and having another axis parallel with the axis of said cylinder, a guide mounting provided with a guide-receiving opening having an axis parallel with the axis of said cylinder, and means interlocking with said mounting and said guide to prevent said guide from turning about its second-mentioned axis. 100

5. An engine comprising, in combination, a cylinder having a piston working therein, a valve having its axis disposed lengthwise of and at an angle to the axis of said cylinder, a valve-lifter axially alined with said valve, means for moving said valve-lifter axially to cause the same to move said 110

valve axially, a valve-lifter guide provided with a valve-lifter guiding bore having its axis alined with said valve, said guide being provided with an outer surface whose axis is parallel with the axis of said cylinder, a guide-mounting provided with a guide-receiving opening parallel with the axis of

5 said cylinder, valve lifter guide positioning means, and valve lifter guide clamping means.

10 In testimony whereof, I have signed my name to this specification.

NIKLAS WINBLAD.
